UNITED STATES PATENT OFFICE.

ELMER O. BEARDSLEY AND WALTER F. PIPER, OF CHICAGO, ILLINOIS, ASSIGNEES TO THE BEARDSLEY & PIPER COMPANY, OF CHICAGO, ILLINOIS, A CORPORATION OF ILLINOIS.

MOLDING MACHINE.

Application filed November 6, 1922. Serial No. 599,191.

To all whom it may concern:

Be it known that we, ELMER O. BEARDSLEY and WALTER FRANCIS PIPER, both citizens of the United States, and residents of Chicago, in the county of Cook and State of Illinois, have invented certain new and useful Improvements in Molding Machines, of which the following is a full, clear, and exact description.

10. The invention relates to molding machines.

In making molds by high speed sand projectors, the flasks are usually overfilled to insure the complete filling thereof and the 15 excess is stricken off by a bar. This excess is considerable in volume, particularly where the flasks are rapidly filled, as is the case when rotary high speed sand projectors are used. One object of the invention 20 is to provide means for feeding the strike-off sand back to the molding machine.

Another object of the invention is to provide improved means for delivering flasks to and from the sand projectors to facilitate 25 the work of the machine and to increase its output.

Other objects of the invention will appear from the detailed description.

30. The invention consists in the several novel features hereinafter set forth and more particularly defined by claims at the conclusion hereof.

In the drawings: Fig. 1 is a plan of a 35 machine embodying the invention. Fig. 2 is a side elevation. Fig. 2^a is a detail of the elevator-chain and buckets. Fig. 2^b is a section on line 2^b—2^b of Fig. 2. Fig. 3 is a section on line 3—3 of Fig. 1. Fig. 4 is a section on line 4—4 of Fig. 1. Fig. 5 is a side elevation of the gearing for propelling the machine. Fig. 6 is a section on line 6—6 of Fig. 1.

The invention is exemplified in a structure which comprises a truck mounted upon wheels adapted to travel on rails laid in the molding room floor; a molding machine of the projector type which is mounted on the truck; conveying and elevating mechanism for delivering sand from a longitudinal pile on the floor in front of the machine to the projector on the truck; and

mechanism for propelling the truck so that it will progressively advance into the pile to keep the projector continuously supplied with sand.

The truck-frame comprises sides 10 and 11 which are rigidly secured together by pipes 12 and 13. Pipe 12 is secured to said frame-sides by U-bolts 14 and pipe 13 is secured to said sides by U-bolts 15. The rear portions of the frame-sides of the truck are also cross-connected by a plate or bar 16 which is bolted to the frame-sides as at 17 (Fig. 3). The front of the truck is carried by a pair of traction-wheels 21 which have toothed peripheries to engage correspondingly toothed portions 23 of rails 24 which are set into the floor of the molding room. The rear of the truck is supported by wheels 27 on stud-axles 28 which are carried by the frame-sides 10 and 11. A shaft 26 extends through pipe 13 and is keyed at its ends to the hubs of the traction-wheels so that they will rotate together 75 and evenly propel both sides of the machine.

The sand projector or molding machine illustrated is substantially of the construction exhibited in Patent No. 1,408,493, dated 80 March 7, 1922, and comprises a supporting standard 35 fixed on the truck, a jib 44 pivoted to the standard so as to swing horizontally, an arm 45 pivoted to the outer end of the jib, a sand projector 46 containing 85 a rotor driven by an electric motor 47 which is mounted to swing horizontally with the arm 45, a vibratory conveyor-chute 48 containing a riddle 48^a and mounted to swing with jib 44, a belt 50 mounted to swing with 90 said arm and for feeding sand from chute 48 to the projector, and a case 49, containing mechanism for vibrating the chute 48 and including an electric motor, all of which may be of the construction set forth in said 95 patent, to which reference may be had for a more detailed description thereof. Standard 35 is disposed at one side of the truck and adjacent the front thereof, so that the projector will be movable horizontally over flasks adjacent the center of the truck.

Standard 35 is clamped to pipe 13 by U-bolts 37 and bolted to a bracket 36 which is secured to a standard 60. This mech-

anism exemplifies a sand projector which is mounted on the truck and is movable laterally so as to discharge sand into all portions of flasks below the projector.

5 The sand is supplied to the projector from a pile on the floor ahead of the truck by a cross-conveyor consisting of a screw 54 on a cross-shaft 55. An inclined trough-plate 58 in the rear of the conveyor-screw cooperates with the latter to direct sand to one side of the machine. Plate 58 is secured to and supported from frame-pipe 13 by U-bolt clamps 57. Conveyor-screw 54 and plate 58 terminate inwardly of frame-side 10 and a sand elevator is disposed between one end of the conveyor and said frame-side. This elevator comprises an endless chain 59 and buckets 61 projecting from one side of the chain. Chain 59 passes around a drive-sprocket 62 which is fixed to shaft 55 and elevated idler sprockets 63 and 64 and a lower rear sprocket 65. Sprocket 63 is carried by a shaft 63' which is held in standard 60, the lower end of which is secured to frame-side 10. Sprocket 64 is carried by a shaft 66 which is carried by a lever 67. Said lever is pivoted to a standard 60^a and is operated by a tension device 67^a to cause sprocket 64 to keep the elevator chain taut. Standard 60^a is secured to frame-side 10 by U-bolts 68 and to standard 60 by a bracket 69. The reach of the elevator between sprockets 63 and 64 extends over the inner end of conveyor-chute 48, so that the elevator buckets will discharge the sand directly into the chute. This construction exemplifies mechanism for conveying sand from a pile in front of the truck to one side thereof and elevating it for delivery to the projector on the truck.

An electric motor 70 is secured on frame-side 10 of the truck frame and drives the sand conveyor and elevator and the propelling mechanism for the truck. Shaft 55 of conveyor 54 is driven from said motor by a pinion 71 on the motor shaft, a gear 72 meshing with pinion 71 and mounted on a stud 73 carried by frame-side 10, a pinion 74 which is rigid with gear 72 and a gear 75 meshing with pinion 74 and fixed to one end of shaft 55. The elevator is driven by sprocket 62 which is fixed to shaft 55. The traction-wheels are driven to propel the truck to cause it to progressively advance into the sand pile, by an eccentric pin 76 on one end of shaft 55, a pawl 78 pivoted to and operated by said pin, a ratchet wheel 79 engaged by said pawl, and a pinion 80 which is rigid with said ratchet and rotates on a stud 81 on frame-side 11. Pinion 80 has teeth conforming to the teeth on the traction wheels 21 and engages one of them, the other being driven through cross-shaft 26. A dog 82 prevents retraction of ratchet 79.

65 A desideratum in the operation of high

speed sand projectors is to deliver the flasks into and out of the position in which they are filled by the projector with facility to increase the work of the machine. For this purpose, a rotatable carrier D is provided. A series of flask-supports 84 are supported on this carrier to bring flasks in rotative succession into position to be filled and so that a flask may be placed on the support for delivery to the projector and a filled flask may be removed from its support while another flask is being filled. This rotatable carrier is formed of a disk of boiler plate 85 which is secured to a socket or housing 86. Housing 86 is sustained so it is horizontally rotatable by roller-bearings 87 which are carried by a hollow standard 88 which is secured by bolts 89 to the cross-bar 16 of the truck frame. A roller 90 on an axle 91 in said standard is adapted to ride on a central rail 92 to render the standard, which supports the carrier, vertically rigid. The marginal portion of the carrier is supported by a pair of grooved horizontal rollers 93, each of which is mounted on a stud-shaft 94 which is held in a bearing 95 which is clamped to frame-pipe 13 by U-bolts 96. A gear-ring 97 is secured by bolts 98 to the margin of the disk 85. A pinion 99 meshes with the ring gear 97 to rotate the flask carrier. This pinion is secured to the lower end of a shaft 100 which is carried by a bearing 101 on frame-side 10. A bevelled gear 102 is fixed to the upper end of shaft 100. Said gear is driven to drive pinion 95 and the carrier D by power taken from sprocket 65 which is driven by the elevator chain 59. A sprocket 103 fixed to rotate with sprocket 65 drives a chain 104 which passes around and drives a sprocket 105 on a shaft 106. Said shaft is supported in a bearing 107 formed in frame-side 10 and drives a bevelled gear 108 which meshes with bevelled gear 102. This gearing exemplifies mechanism for continuously rotating the flask-carrier. Being continuously driven, this carrier will deliver the flasks placed on the supports 84 to the space beneath the convenient range of the sand projector, in rotative succession and also carry them away. As a result, while one flask is being filled by the projector, one or more empty flasks can be placed on the supports rotating towards the projector. At the same time, an operator may strike off the flask which has been previously filled and can remove that flask. This construction exemplifies driving mechanism for the carrier which delivers the flasks to and from the projector.

125 The carrier disk 85 also receives the excess sand which is stricken from the filled flask and the spill from the projector. The operator usually strikes the sand from the flask as soon as it has passed to the right hand side of the machine and before

removing the flask from its support 84. The strike-off sand falls on disk 85 so that it will rotate therewith. In its rotation with the disk, the sand will engage stationary guide strips 110, 111. Guide 110 is resilient and secured to an arm 112 which is fixed on the upper end of a post 113 which is fixedly secured in hollow standard 88. Guide 111 is secured to a bracket 95. Guide 110 is resilient so it may be forced toward the axis of the disk by the reduced stems 115 of the flask supports 84 in their rotation to permit said stems to pass between guides 110 and 111. These guides direct the sand to that portion of the carrier disk which is adjacent frame-side 10 and the rear of the sand elevator. Rake-bars 115 are secured to a bar 116 which is suspended at its rear end by a link 117 which is hung on frame-side 10 and has its front end connected to a crank 118 on the shaft of sprocket 65. These bars rake or toss the sand from disk 85 into the path of the forwardly and horizontally moving buckets 61, which will reconvey the sand from the disk with the sand from the conveyor-screw 54 upwardly for delivery to the projector. This construction exemplifies means for catching the spill from the projector and the strike-off sand from the filled flasks and delivering it to the sand supply for the projector, so that it will be again delivered to the projector. This results in avoiding the loss of the use of this sand during a run of the machine.

The operation of the machine will be as follows: When the machine is in use, the truck will be advanced slowly into the sand in the pile in front of the machine and one end of the screw 54 will deliver sand to the free side of the elevator-buckets 61. The latter will lift the sand in regular volume and deliver it into the conveyor-chute 48 which will deliver it onto the feed-belt 50 for delivery into the casing of the sand projector. Carrier D will be continuously rotated. The operator will place empty flasks upon the supports 84 while they are moving forwardly with the carrier. As each flask reaches a point adjacent and beneath the projector, the operator will shift the projector to project wads of sand at high speed into the flasks and fill them. As the flasks are moving rearwardly and after they have been filled, an operator strikes off the sand which will be deposited on the carrier disk and then removes completed molds from the carrier so that the supports may receive the empty flasks. Considerable sand is discharged by the projector outside of the flasks and the spill, together with the strike-off sand, will be caught by the carrier disk and delivered to the sand elevator, so that the sand will be again used in filling flasks.

The operation may be continuously carried on, because of the continuously moving

mechanism for delivering flasks to and from the projector.

The invention exemplifies a tractor type sand projector which is provided with mechanism for keeping the projector supplied with flasks for filling, so that the molds may be quickly produced and so that the machine will have a maximum output; which comprises means for delivering the strike-off sand and spill back to the projector; which includes a rotary disk for feeding sand to the elevator; and in which the cross-conveyor screw delivers the sand to the free side of elevator-buckets which are entirely supported at the other side.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In a machine for making molds, the combination of a sand projector, mechanism to operate the projector to forcibly deliver sand into flasks, mechanism for feeding sand to the projector, means for conveying flasks to the projector, and mechanism for driving said conveying mechanism to bring flasks successively into and out of position beneath the projector.

2. In a machine for making molds, the combination of a sand projector, mechanism for feeding sand to the projector, means to movably support the projector so it may be manually shifted over flasks, means for conveying flasks to the projector, and mechanism for driving said conveying mechanism to successively bring flasks into and out of position beneath the projector.

3. In a machine for making molds, the combination of a sand projector, mechanism for feeding sand to the projector, means to movably support the projector so it may be manually shifted over flasks, means for conveying a series of flasks to the projector, and mechanism for driving said conveying mechanism to successively bring flasks into position beneath the projector.

4. In a machine for making molds, the combination of a sand projector mechanism to operate the projector to forcibly deliver sand into flasks, mechanism for feeding sand to the projector, a rotary conveyor for flasks, and mechanism for driving said conveyor to successively bring flasks thereon into and out of filling position beneath the projector.

5. In a machine for making molds, the combination of a sand projector, means to movably support the projector so it can be manually shifted over a flask, mechanism for feeding sand to the projector, a rotary conveyor for flasks and mechanism for driving

said conveyor to successively bring a flask thereon into and out of filling position beneath the projector.

6. In a machine for making molds, the combination of a sand projector mechanism to operate the projector to forcibly deliver sand into flasks, mechanism for feeding sand to the projector, a rotary conveyor adapted to hold a series of flasks, and mechanism for driving said carrier to successively bring flasks thereon into and out of filling position beneath the projector.

7. In a machine for making molds, the combination of a sand projector mechanism to operate the projector to forcibly deliver sand into flasks, mechanism for feeding sand to the projector, a conveyor for successively delivering flasks to and from the projector, and mechanism for continuously driving said conveyor.

8. In a machine for making molds, the combination of a sand projector mechanism to operate the projector to forcibly deliver sand into flasks, mechanism for feeding sand to the projector, a rotary conveyor for delivering flasks to and from the projector in rotative succession, and mechanism for continuously driving said conveyor.

9. In a machine for making molds, the combination of a sand projector, means to movably support the projector so it can be shifted over a flask, mechanism for feeding sand to the projector, a rotary conveyor adapted to hold a series of flasks and for delivering them to and from the projector in rotative succession, and mechanism for continuously driving said conveyor.

10. In a machine for making molds, the combination of a sand projector mechanism to operate the projector to forcibly deliver sand into flasks, mechanism for feeding sand to the projector, a conveyor adapted to hold a plurality of flasks and carry them in succession to and from the filling position beneath the projector, and mechanism for driving the conveyor connected to be driven with the sand feeding means.

11. In a machine for making molds, the combination of a sand projector, mechanism for feeding sand to the projector, a rotary conveyor adapted to hold a plurality of flasks and carry them in rotative succession to and from the filling position beneath the projector, and mechanism for driving the conveyor, geared to and driven by the sand-feeding means.

12. In a machine for making molds, the combination of a sand projector, mechanism for feeding sand to the projector comprising an elevator, a conveyor adapted to hold a plurality of flasks and carry them in succession to and from the projector, and mechanism for driving the carrier, geared to and driven by said elevator.

13. In a machine for making molds, the

combination of a truck, mechanism for propelling the truck, a sand projector mounted on the truck mechanism to operate the projector to forcibly deliver sand into flasks, means for feeding sand to the projector, a conveyor movable with the truck and adapted to hold a plurality of flasks and successively deliver them into and out of filling position below the projector, and mechanism for driving said conveyor.

14. In a machine for making molds, the combination of a truck, mechanism for propelling the truck, a sand projector mounted on the truck mechanism to operate the projector to forcibly deliver sand into flasks, means for feeding sand to the projector, a conveyor movable with the truck and adapted to hold a plurality of flasks and successively deliver them into and out of filling position below the projector, and mechanism for driving said conveyor operable with the propelling mechanism.

15. In a machine for making molds, the combination of a truck, mechanism for propelling the truck, a sand projector mounted on the truck, means for feeding sand to the projector, a conveyor movable with the truck and adapted to hold a plurality of flasks and successively deliver them into and out of filling position below the projector, and mechanism on the truck for driving said conveyor.

16. In a machine for making molds, the combination of a truck, mechanism for propelling the truck, a sand projector mounted on the truck, means for feeding sand to the projector, a conveyor movable with the truck and adapted to hold a plurality of flasks and successively deliver them into and out of filling position below the projector, mechanism for driving said conveyor and a motor on the truck connected to drive said conveyor.

17. In a machine for making molds, the combination of a truck, mechanism for propelling the truck, a sand projector mounted on the truck, means for feeding sand to the projector, a conveyor movable with the truck and adapted to hold a plurality of flasks and successively deliver them into and out of filling position below the projector, mechanism for driving said conveyor, and a motor on the truck connected to drive said conveyor and the sand-feeding means.

18. In a machine for making molds, the combination of a truck, mechanism for propelling the truck, a sand projector mounted on the truck, means for feeding sand to the projector, a conveyor movable with the truck and adapted to hold a plurality of flasks and successively deliver them into and out of filling position below the projector, mechanism for driving said conveyor, and a motor on the truck connected to drive said conveyor and the propelling mechanism.

19. In a machine for making molds, the combination of a truck, mechanism for propelling the truck, a sand projector mounted on the truck, means for feeding sand to the projector, a conveyor movable with the truck and adapted to hold a plurality of flasks and successively deliver them into and out of filling position below the projector, mechanism for driving said conveyor, and a motor on the truck connected to drive said conveyor, the sand feeding means and the propelling mechanism. 75
20. In a machine for making molds, the combination of a truck, mechanism for propelling the truck, a sand projector mounted on the truck mechanism to operate the projector to forcibly deliver sand into flasks, means on the truck for feeding sand to the projector, a rotary conveyor movable with the truck to hold a plurality of flasks and to deliver them into and out of filling position under the projector, and mechanism for driving said conveyor. 80
21. In a machine for making molds, the combination of a truck, mechanism for propelling the truck, a sand projector mounted on the truck mechanism to operate the projector to forcibly deliver sand into flasks, means on the truck for feeding sand to the projector, a rotary conveyor mounted on the truck to hold a plurality of flasks and to deliver them into and out of filling position below the projector, and mechanism on the truck for driving said conveyor. 85
22. In a machine for making molds, the combination of a truck, a sand projector mounted on the truck, means on the truck for feeding sand to the projector, a rotary conveyor mounted on the truck to hold a plurality of flasks and to deliver them into and out of filling position below the projector, gearing on the truck for driving said conveyor, and a motor on the truck for driving said gearing. 90
23. In a machine for making molds, the combination of a truck, a sand projector mounted on the truck, means on the truck for feeding sand to the projector, a rotary conveyor mounted on the truck to hold a plurality of flasks and to deliver them into and out of filling position below the projector, gearing on the truck for driving said conveyor, and a motor on the truck for driving said gearing, and said sand-feeding means. 95
24. In a machine for making molds, the combination of a truck, mechanism for propelling the truck, a sand projector mounted on the truck, means on the truck for feeding sand to the projector, a rotary conveyor mounted on the truck to hold a plurality of flasks and to deliver them into and out of filling position below the projector, gearing on the truck for driving said conveyor, and a motor on the truck for driving said conveyor. 100
25. In a machine for making molds, the combination of a sand projector, means to feed sand to the projector, means to support the projector for horizontal movement over and to deliver sand into all portions of a flask, and means to receive the strike-off sand from the flasks and deliver it for reconveyance to the projector. 105
26. In a machine for making molds, the combination of a sand projector, means to feed sand to the projector, means to support the projector for horizontal movement over and to deliver sand into all portions of a flask, a conveyor to receive the strike-off sand from the flasks and excess sand and deliver it for reconveyance to the projector, and mechanism for continuously driving the conveyor. 110
27. In a machine for making molds, the combination of a sand projector, means to feed sand to the projector, means to movably support the projector for movement over a flask, means to receive the strike-off sand from the flasks, and deliver it to said feed-means, and mechanism for conjointly driving the feed-means and the receiving means. 115
28. In a machine for making molds, the combination of a sand projector, means to feed sand to the projector, means to movably support the projector for movement over a flask, a rotary conveyor to receive the strike-off sand from the flasks and to deliver it for reconveyance to the projector, and mechanism for driving said conveyor. 120
29. In a machine for making molds, the combination of a sand projector, means to feed sand to the projector, means to movably support the projector for movement over a flask, a rotary conveyor to receive the strike-off sand from the flasks and to deliver it to the feed-means, and mechanism for continuously driving the conveyor. 125
30. In a machine for making molds, the combination of a sand projector, means to feed sand to the projector comprising an elevator, means to movably support the projector for movement over a flask, a rotary conveyor adapted to receive the strike-off sand from the flasks and to deliver it to the elevator, and mechanism for conjointly driving said conveyor and elevator. 130
31. In a machine for making molds, the combination of a sand projector, means to feed sand to the projector, means to support the projector for horizontal movement over and to deliver sand into all portions of a flask, means to receive the spill from the projector and to deliver the sand to the feed means, and mechanism for driving the receiving means. 135
32. In a machine for making molds, the combination of a sand projector, means to feed sand to the projector, means to mov-

ably support the projector for movement over a flask, a rotary conveyor to receive the spill from the projector and deliver it to the projector for reconveyance, and mechanism 5 for driving the conveyor.

33. In a machine for making molds, the combination of a sand projector, means to feed sand to the projector, means to mov- 10 ably support the projector for movement over a flask, a conveyor for receiving the spill from the projector and delivering it to the feed means, and mechanism for con- jointly and continuously driving the conveyor and the feed means.

34. In a machine for making molds, the combination of a truck, mechanism for pro- 15 pelling the truck, a sand projector on the truck, mechanism for feeding sand to the projector, a conveyor movable with the truck 20 to receive the strike-off from the flasks and carry it to the feed-means, and mechanism for driving the conveyor.

35. In a machine for making molds, the combination of a truck, mechanism for pro- 25 pelling the truck, a sand projector on the truck, mechanism for feeding sand to the projector, a disk movable with the truck to receive the strike-off from the flasks and 30 carry it to the feed-means, and mechanism for driving the disk.

36. In a machine for making molds, the combination of a truck, mechanism for pro- 35 pelling the truck, a sand projector on the truck, mechanism for feeding sand to the projector, a conveyor mounted on the truck to receive the spill from the projector and 40 carry it to the feed-means, and mechanism for driving the conveyor.

37. In a machine for making molds, the combination of a truck, mechanism for pro- 45 pelling the truck, a sand projector on the truck, mechanism for feeding sand to the projector, a disk mounted on the truck to receive the spill from the projector and 50 carry it to the feed-means, and mechanism for driving the disk.

38. In a machine for making molds, the combination of a truck, mechanism for propelling the truck, a sand projector on 55 the truck, mechanism for feeding sand to the projector, a conveyor mounted on the truck to receive the strike-off sand from the flasks and carry it to the feed-means, and mechanism on the truck for driving the conveyor.

39. In a machine for making molds, the combination of a truck, mechanism for propelling the truck, a sand projector on the truck, mechanism for feeding sand to 60 the projector, a disk mounted on the truck to receive the strike-off sand from the flasks and carry it to the feed-means, and mechanism on the truck for driving the disk.

40. In a machine for making molds, the 65 combination of a sand projector, means to

feed sand to the projector, means to mov- ably support the projector for movement over a flask, a conveyor mounted on the truck, and flask supports on the carrier, 70 said conveyor having means to receive the strike-off sand from flasks and the spill from the projector and to deliver it for reconveyance to the projector.

41. In a machine for making molds, the combination of a sand projector, means to feed sand to the projector, means to mov- 75 ably support the projector for movement over a flask, a rotary conveyor mounted on the truck, flask supports on the conveyor, 80 said conveyor having means to receive the strike-off sand from flasks and the spill from the projector and to deliver it for reconveyance to the projector, and mechanism for driving the conveyor.

42. In a machine for making molds, the combination of a sand projector, means to feed sand to the projector, means to mov- 85 ably support the projector for movement over a flask, a disk mounted on the truck, 90 flask supports on the disk, said disk receiv- ing the strike-off sand from flasks and the spill from the projector and delivering it to the feed means, and means for driving the disk.

43. In a machine for making molds, the combination of a laterally movable sand projector, mechanism for feeding sand to the projector, a rotatable conveyor, flask- 95 supports on the conveyor movable into and out of filling position under the projector, the conveyor having means to receive the strike-off sand from the flasks and the spill from the projector, a stationary sand-deflector over said conveyor, and mechanism 100 for driving the conveyor.

44. In a machine for making molds, the combination of a truck, mechanism for propelling the truck, a sand projector movably mounted on the truck, mechanism for feeding sand to the projector, a rotatable conveyor mounted on the truck, flask-supports 105 on the conveyor, movable into and out of filling position under the projector, the conveyor having means to receive the strike-off sand from the flasks and the spill from the projector, a stationary sand-deflector over said conveyor, and mechanism for driving the conveyor.

45. In a machine for making molds, the combination of a laterally movable sand projector, a sand elevator comprising an endless chain and a pair of wheels spaced apart for supporting the upper portion of said chain, a conveyor-chute having a portion thereof underlying the elevator between said wheels, so that the sand will be dumped directly into the chute, and mechanism for driving the elevator.

46. In a machine for making molds, the combination of a truck, mechanism for pro-

10 pelling the truck, a sand projector movably mounted on the truck, a sand elevator on the truck and comprising an endless chain and a pair of wheels spaced apart for supporting the upper portion of said chain, a conveyor chute having a portion thereof underlying the elevator between said wheels, so that the sand will be dumped directly into the chute, and mechanism for driving 10 the elevator.

47. In a machine for making molds, the combination of a laterally movable sand projector, means to feed sand to the projector comprising an elevator and a rotary 15 disk, mechanism for driving the disk, and means to feed the sand from the disk to the elevator.

48. In a machine for making molds, the combination of a truck, a laterally movable 20 sand projector on the truck, means on the truck to feed sand to the projector comprising an elevator provided with buckets and a rotary disk, mechanism for driving the disk, and means to rake the sand from the 25 disk to the elevator.

49. In a machine for making molds, the combination of a truck, means on the truck

to deliver sand into a flask, mechanism for feeding sand to the projector comprising a single endless chain and buckets fixed on 30 one side of said chain, and means for driving said chain and means to deliver sand to the unattached side of the buckets.

50. In a machine for making molds, the combination of a truck, a movably mounted sand projector on the truck mechanism for feeding sand to the projector comprising a single endless chain and buckets fixed on 35 one side of said chain and a screw-conveyor terminating adjacent the other side of the 40 buckets.

51. In a machine for making molds, the combination of a truck having wheels at its sides, a movably mounted sand projector on the truck, mechanism for feeding sand 45 to the projector comprising a rotary table mounted on the truck, mechanism for driving the table, and a central support for the table.

Signed at Chicago, Illinois, this 17th day 50 of January, 1922.

ELMER O. BEARDSLEY.
WALTER F. PIPER.
